(57) **CLAIM**

The ornamental design for a susceptor for microwaveable food, as shown and described.

DESCRIPTION

FIG. 1 is a top plan view of a susceptor for microwaveable food showing the new design;

FIG. 2 is a bottom plan view thereof;

FIG. 3 is a side elevational view thereof, the opposite side elevational view being the same as FIG. 3; and,

FIG. 4 is another side elevational view thereof, the opposite side elevational view being the same as FIG. 4.
